UNITED STATES PATENT OFFICE.

JOHN H. GOODFELLOW, OF LOWELL, MASSACHUSETTS, ASSIGNOR TO CONSOLIDATED SAFETY PIN COMPANY, OF BLOOMFIELD, NEW JERSEY.

MACHINE FOR CARDING SAFETY-PINS.

SPECIFICATION forming part of Letters Patent No. 683,599, dated October 1, 1901.

Application filed August 16, 1898. Serial No. 688,667. (No model.)

To all whom it may concern:

Be it known that I, JOHN H. GOODFELLOW, a citizen of the United States, residing in Lowell, in the county of Middlesex, State of Massachusetts, have invented certain new and useful Improvements in Machines for Carding Safety-Pins, &c., of which the following is a specification, reference being had to the accompanying drawings, forming a part hereof.

The object of this invention is to provide a machine for attaching safety-pins to cards or strips of paper in a rapid and satisfactory manner, the hand-carding of such pins, which has been practiced hitherto on account of the peculiar character of the articles to be handled, being necessarily slow and expensive. The machine in which the invention is embodied and has been illustrated in the accompanying drawings for purposes of explanation comprises means for separating the pins from a collected mass or bulk, means for sorting them, so that they shall be presented properly to the devices which follow, means for taking them from the sorting devices and presenting them to the card or paper, means for preparing and presenting the card or paper, and various other parts which are more or less incidental to certain of the mechanical devices above referred to. It is to be understood, however, that not all of these various mechanical devices are of necessity associated in one machine and that the invention is not to be restricted to their application together to a single structure nor to the precise construction and arrangement of the various devices which are herein shown and described.

In the drawings, Figure 1 is a front side elevation of a machine which embodies the several features of the invention. Fig. 2 is a plan view of the same, parts below the work-table being indicated by dotted lines. Fig. 3 is an end elevation of the machine seen from the left of Figs. 1 and 2. Fig. 4 is a transverse section on the plane indicated by the dotted line 4 4 of Fig. 2. Figs. 5, 6, 7, and 8 are detail views of parts to be referred to hereinafter.

The work table or bed of the machine upon or with relation to which most of the working parts are supported is represented at A,

being mounted upon a suitable frame A'. A driving-shaft B is supported in suitable bearings beneath the table and is provided with a driving-pulley C and a loose pulley C'. 55 Various cams and eccentrics are fixed upon the shaft B and are arranged to cause various mechanical devices to perform their allotted functions at predetermined intervals of time, as more fully described hereinafter. 60

A hopper or reservoir D is supported at a suitable elevation above the work-table to receive the safety-pins in mass or bulk. Its bottom is inclined or slotted, and in the slots are mounted blades d, which are pivoted at 65 the rear, while their forward ends are united and through a suitable finger d' rest upon a projection d² from a vertically-reciprocating blade d³. The latter is wholly in front of the reservoir or hopper D, and its upper edge d⁴ 70 is inclined at the same angle as the bottom of the hopper, with which it is substantially flush when the blade is in its lowest position. The blade d³ is reciprocated by any suitable means, such as the link d⁵, lever d⁶, and cam 75 or eccentric D' on the shaft B. The blades d do not fall below the bottom of the hopper, but at each upward movement of the blade d³ the finger d' is struck by the projection d², so that the mass of pins in the hopper is 80 shaken up, causing the pins to slide forward one after another on the extended bottom of the hopper, suitable stops being provided to prevent the pins from sliding beyond the vertically-reciprocating blade d³. As the side 85 walls which bound the extension of the hopper-bottom converge, as clearly shown in Fig. 2, the pins are guided over the reciprocating blade d³, by which they are lifted, straddling its upper edge, as clearly shown in Fig. 8. 90

A notched feed-wheel E is supported upon a suitable standard in line with the vertically-reciprocating blade d³ and in close proximity thereto, being driven by any suitable means, as by a cord e and pulleys e¹ e², from the driving-shaft B. Each notch e³ of the wheel E is of such a depth as to receive from the inclined upper edge d⁴ of the reciprocating blade d³ only one safety-pin, the safety-pin sliding down the said inclined edge against 95 the feed-wheel. As the feed-wheel rotates the safety-pins are carried over, as clearly 100

shown in Fig. 8, and are deposited upon the sorting-blade F, which is inclined, so as to permit the pins to slide downward upon it, and being at first substantially vertical and straddling the feed-wheel, as at f, is gradually flattened out, with the farther edge depressed somewhat, so that all of those safety-pins which pass onto the flattened portion f' with the pin-points uppermost, as shown in Figs. 7 and 8, will slip off into a suitable receptacle F', while the remaining pins will slide down toward the lower end of the sorting-blade. From the lower end of the sorting-blade the pins are permitted to pass one at a time to the devices which present them to the card or paper. A trip mechanism is provided for the purpose of releasing the pins one by one, such trip mechanism comprising an arm G, which is pivoted upon the side of a vertical standard and is forked at its upper end, one part g underlying the sorting-plate F and having spurs g', which project upwardly through openings in said plate, while the other part g² overlies said plate F. As the arm or bar G is rocked upon its pivot the spurs g' are withdrawn from the plate F, permitting one pin which before was lodged against them to slide down against the upper part or arm g², which lies farther forward, and by the same movement is brought against the upper side of the plate, thus stopping the pin which has been released by the spurs. As the arm or bar rocks backward the spurs rise through the plate F to detain the next pin, while the upper arm g² releases that held by it and permits it to slide farther down the plate F. The arm or bar G is conveniently operated by a lever g³, which is pivoted upon the work-table A and is drawn in one direction by a spring g⁴, while its short arm g⁵ bears against or at the proper time makes contact with another lever, hereinafter to be referred to. The pins slide from the end of the sorting-plate F through a suitable guide-chute F² into the grasp of the conveying or transferring device. This last-named device comprises two gripper-jaws H, which are mounted to slide in a suitable guideway affixed to the table A, the said jaws being pivoted together upon a pin h and being provided at their forward ends with studs h' to enter the eye of the pin, as clearly shown in Fig. 4. The jaws are normally pressed apart by a spring h² and are caused to reciprocate together in the guideway provided therefor by any suitable means, such as a forked lever h³, (which also operates the trip-arm G, above referred to, through the lever g³,) a connecting-rod h⁴, and a cam or eccentric H' on the shaft B. In order that the jaws H may close and open at the proper time, they are made to slide forward between two operating-jaws H², which are pivoted upon the work-table and form the forward part of the guideway. The rear ends of these operating-jaws H² are formed with cam-faces h⁵ to cause the jaws H to close upon the pin as soon as they commence their forward move-

ment, and the forward or free ends of said operating-jaws are engaged by levers h⁶, operated by cams H³ on the shaft B. The cams H³ are so placed that they cause the operating-jaws H² to open, thereby releasing the gripper-jaws H and permitting them to release the pin which has been held by them at the moment when the gripper-jaws have reached the limit of their forward stroke. The point of the safety-pin is caused to enter the card or paper during the forward movement of the gripper-jaws, and after it has been inserted in the card or paper it is desirable to close the pin, causing its guard to engage the point. For this purpose an anvil-block I, having a narrow slot i in its upper face, is mounted just below the path of movement of the pin-point and is caused to rise after the pin-point has passed above it by any suitable means, such as a lever i' and a cam or eccentric I' on the shaft B. With the anvil co-operates a presser K, which operates upon the upper or guard member of the pin, pressing it down to cause the guard to engage the pin-point after the latter has penetrated through the card or paper. As represented, the presser consists of a lever suitably notched, as at k, to engage the pin and operated at the proper time by any suitable means, as a connecting-rod k' and a cam or eccentric K' on the shaft B. So far as concerns the operation of the devices already described, the card or paper to which the pins are to be affixed may be fed, prepared, and supported by hand or by any suitable mechanism; but the machine shown in the drawings is represented as provided with mechanical devices for handling a continuous strip of paper. As represented in the drawings, the paper is supplied from a roll L, which is mounted in suitable standards and is provided with a suitable brake l. From the roll it passes through a crimper or folder l', which gives to the strip of paper the form necessary to permit it to be engaged readily by the pin-points. The crimper or former consists of a suitably-shaped metallic shell and base, which are cut away to permit the feed-rolls l² l³ to engage the paper strip and are also cut away in line with the anvil I to permit the pin to be inserted, the shell being extended farther to form a convenient guide for the strip and to permit the cutter, hereinafter referred to, to operate properly. The converging sides of the shell, which is open below, turn the margins of the strip down, so that the strip at the point where the pins are inserted is in section an inverted U. The lower feed-roll l² may be mounted in fixed bearings. The upper feed-roll is preferably mounted in arms l⁴, which are pivoted upon the table and are provided with set-screws l⁵, whereby the pressure of the upper roll may be regulated. The roll l³ is provided with a ratchet-wheel l⁶, which is fixed to the shaft of the roll, the said ratchet-wheel being engaged by a pawl l⁷, carried by an arm l⁸, which is also mounted, but loosely, on the shaft of

- the feed-roll. It is desirable that the strip should be fed forward more rapidly at certain times than at others in order to leave suitable spaces at intervals where the strip can be cut to form shorter lengths, and mechanism has been devised and will presently be described whereby this result can be accomplished. The arm l^8 , above referred to, is connected to one end of a rod or bar M , which is supported to slide longitudinally and is provided with a projection m . Parallel with the rod or bar M is a short fixed shaft m' , upon which is mounted a sleeve m^2 , having fixed thereon a ratchet or crown wheel m^3 . A pawl m^4 is mounted on the frame to engage said ratchet and cause the forward movement thereof in a rotary direction as the ratchet is brought in contact therewith through its longitudinal reciprocatory movement on its axis, which is effected through the medium of a bell-crank lever m^5 , a connecting-rod m^6 , and a cam or eccentric M' on the shaft B . The rear edge of the ratchet-wheel is adapted to engage the projection m on the rod or bar M in its movement to the rear, whereby a short movement of the bar is effected. The rear edge of the ratchet-wheel is also provided with one or more studs m^7 , disposed at regular intervals, so that when one of these studs is brought into line with the projection m and the ratchet-wheel is moved to the rear, or to the left in Fig. 1, the movement of the rod or bar M is commenced earlier and has a greater extent. The shorter movement of the bar causes a sufficient movement of the feed-roll to advance the paper strip sufficiently to receive the next pin in succession, while the longer movement of the bar in the same manner causes the strip to be fed forward a much longer distance, leaving a space for the convenient counting of the pins or where the strip can be cut.
- The cutter-blade N is suitably mounted at the end of the work-table and is held normally in its elevated position by a spring n . It is drawn down to cut the strip at the proper time by a lever n' , operated by a cam N' on the shaft B . In order that the cutter may be operated at the proper intervals, the cam N' is secured to a sleeve n^2 , which is free to slide longitudinally on the shaft B , but is compelled to rotate therewith, and the cam itself normally stands out of line with the lever n' . The end of the sleeve is formed with a cam-nose n^3 to coöperate with a corresponding cam n^4 , which surrounds the shaft B , but is fixed to the framework. The sleeve is grooved and engaged by a lever n^5 , the end of which stands in the path of movement of the rod or bar M , so that it is struck thereby as said bar approaches the limit of its longer movement, thereby causing the cutter to be operated at the proper time to sever the strip in the space between successive groups of pins. As soon as the cam N' has completed the movement of the cutter the fixed cam n^4 , acting upon the rotating cam-nose n^3 , will force the cam N' out of line with the cutter-lever n' and through the lever n^5 will push the rod or bar M back, if that is necessary, although the spring m^8 , which restores the rod or bar after its shorter movement, may also restore it after the longer movement.
- In the operation of the machine described the pins in mass are placed in the hopper D and the roll of paper is placed in its bearings and the end of the strip led forward through the former and between the feed-rolls. The machine being then set in motion, the pins are separated, sorted, delivered to the gripper-jaws, and inserted in the paper strip over the anvil, the pin being closed after it has been inserted in the strip. The strip is stationary while the pin is being inserted, but is fed forward step by step as the gripper-jaws retire and at certain intervals is fed forward a longer distance. The operations of the several parts have been described in detail hereinbefore and need not be explained again.
- It will be understood that the invention is not to be limited to the precise construction and arrangement of parts shown in the drawings nor to the combination of various mechanical devices in a common structure.
- I claim as my invention—
1. A device for separating safety-pins comprising a hopper with an inclined and slotted bottom, vibrating blades in said slots, and a vertically-reciprocating blade disposed in an extension of the inclined bottom of the hopper, substantially as shown and described. 90
  2. A device for separating and delivering safety-pins comprising a hopper, a vertically-reciprocating blade having an inclined upper edge to receive the safety-pins from the hopper and to lift the same from the mass, and a notched wheel rotating in line with said blade and in proximity thereto, to receive in its notches the pins from the inclined upper edge of the reciprocating blade, substantially as shown and described. 105
  3. A device for sorting safety-pins consisting of an inclined plate along which the safety-pins can slide, the upper portion of said plate being substantially vertical and the lower portion being gradually flattened out with one edge depressed, substantially as shown and described. 115
  4. The combination with a notched feed-wheel of a sorting-plate to receive safety-pins therefrom, said plate being inclined to permit the safety-pins to slide along the same and having its upper portion substantially vertical and in proximity to said feed-wheel and its lower portion gradually flattened out with one edge depressed, substantially as shown and described. 120
  5. The combination with an inclined sorting-plate having its upper portion substantially vertical and its lower portion flattened out with one edge depressed, of a trip device 130

comprising a bar pivoted to swing in a vertical plane, an arm extended forward from said bar and beneath the sorting-plate, said arm having spurs extended upward through openings in said sorting-plate, and a second arm extended forward from said bar and overlying said sorting-plate, substantially as shown and described.

6. The combination, in a machine of the character described, of reciprocating gripper-jaws normally open, operating-jaws between and in contact with which the gripper-jaws reciprocate, and means to open and close said operating-jaws, substantially as shown and described.

7. The combination, in a machine of the character described, of reciprocating gripper-jaws normally open, pivoted operating-jaws forming a guideway for said gripper-jaws and having cam-faces to close said gripper-jaws and means to open said operating-jaws to release the gripper-jaws, substantially as shown and described.

8. The combination, in a machine of the character described, of reciprocating gripper-jaws to grasp the pin and insert its point in the card or paper, an anvil having a slot to receive one member of the pin, and means to move the same toward and from the card or paper, and a presser and means to actuate

the same to close the pin, substantially as shown and described.

9. A paper-feeding mechanism for a machine of the character described, the same comprising a reciprocating bar and connections therefrom to the feed-rolls, a wheel having one or more studs upon one face adapted to engage said bar, means to reciprocate said wheel longitudinally upon its axis and means to rotate said wheel step by step as it reciprocates, substantially as shown and described.

10. A paper feeding and cutting mechanism for a machine of the character described, the same comprising a reciprocating bar and connections therefrom to the feed-rolls, a cutter, a longitudinally-movable cam and connections therefrom to the cutter, a lever to shift said cam, a wheel having one or more studs upon one face adapted to engage said bar, means to reciprocate said wheel longitudinally upon its axis and means to rotate said wheel step by step as it reciprocates, substantially as shown and described.

This specification signed and witnessed this 6th day of August, 1898.

JOHN H. GOODFELLOW.

In presence of—

JOHN C. BENNETT,
A. I. COBURN.
